[57] CLAIM

The ornamental design for a bowl for a water closet or
the like, as shown and described.

DESCRIPTION

FIG. 1 is a perspective view taken from the top, front
and right side of a bowl for a water closet or the like
showing our new design;

FIG. 2 is a perspective view taken from the bottom,
rear and right side thereof; and

FIG. 3 is a right side elevational view thereof, the left
side being a mirror image of the right side shown.

FIG. 1.

FIG. 2.
